FRANKLIN W. OEHRL, OF PHILADELPHIA, PENNSYLVANIA, ASSIGNOR TO OEHRL
BROTHERS COMPANY, OF PHILADELPHIA, PENNSYLVANIA, A CORPORATION OF
PENNSYLVANIA.

MACHINE FOR MAKING ORNAMENTAL ROPE OR CORD.

1,273,911.

Specification of Letters Patent. Patented July 30, 1918.

Application filed July 1, 1911, Serial No. 636,402. Renewed December 7, 1915. Serial No. 65,638.

To all whom it may concern:

Be it known that I, FRANKLIN W. OEHRL, a citizen of the United States, and a resident of Philadelphia, county of Philadelphia, State of Pennsylvania, have invented certain new and useful Improvements in Machines for Making Ornamental Rope or Cord, of which the following is a specification.

10 My invention has relation to machines employed in the manufacture of ornamental rope or cord of the character in which a plurality of loops or strands are secured between binding threads, the said loops extending around one of the said threads and the body of the loops extending in the form of a continuous spiral longitudinally of and around the said binding threads.

15 The nature and purpose of my invention will become apparent from the detailed description thereof taken in connection with the accompanying drawings which illustrate a convenient embodiment thereof, but it will be understood that changes in the details of construction within the scope of the 20 claims may be made without departing from my invention.

In the drawings:—

Figure 1 is a view partly in section and 25 partly in vertical and longitudinal section;

Fig. 2 is a view of the rear end of the mechanism embodying my invention;

Fig. 3 is a view in elevation of the rear end of the former with certain parts associated therewith; and

Fig. 4 is a longitudinal vertical section of the former with a portion of a cutting member shown in proper cutting position with relation thereto.

40 For the sake of simplicity, I have omitted from the drawings all those parts of the mechanism which are not essential to my invention, such, for instance, as the rack, preferably located at one end of the machine upon which the spools are supported from which the threads or strands which make up the ornamental loops of the ropes or cords are supplied and also the twister which is of known form and operates in 45 known manner by means of which the binding threads (which in effect constitute the core of the rope or cord) are twisted together,

Other omitted parts may be referred to hereinafter.

55 Referring to the drawings, 1 designates the base portion of the frame of the machine having uprights or standards 2 and 3, provided with bearings 4 and 5, in which the revoluble member 6 is journaled.

60 In the form of construction herein illustrated, the revoluble member is cylindrical (though it may be of other peripheral contour) and is illustrated as extending continuously from the upright member or 65 standard at the right hand side of Fig. 1 to and through the bearing in the upright or standard 2.

70 10 designates a gear wheel secured by means of the binding screw 11 to the revoluble member 6. Revolution of the gear wheel 10 (by means not illustrated) causes revolution of the revoluble member 6.

75 The speed of revolution may be such as desired.

12 designates a guide or guiding member for the inner binding thread 13 which guide member is supported upon plugs 14 and 15 secured in the revoluble member 6 and which guide member is held against longitudinal 80 movement by means of the collars 16 secured upon opposite sides of the plug 15.

85 The inner binding thread 13 is taken from the thread upon a spool 20, preferably fast upon a sleeve 21, which is loosely and revolubly mounted upon the revoluble member 6. The thread passes from the spool 20 through loop guides 22 on one arm of the flying arms 23 secured to the revoluble member 6. The purpose of providing two such arms 90 is to maintain the balance of the said revoluble member. The thread passes from the guides 22 through an eye or opening 24 in the revoluble member and thence to the guide member 12.

95 The revoluble member 6 revolves in the direction indicated by the arrow 25 in Fig. 2 of the drawings, and the thread upon the spool 20 is so wound that in being drawn therefrom the spool is rotated in the same 100 direction. By reason, therefore, of the connection of one of the flying arms 23 with the thread which is drawn from the spool 20, the spool is caused to revolve with the revoluble member 6 and in addition thereto 105 is given an additional speed of rotation or

revolution by the drawing off of the binding thread 13 by means of the twister hereinbefore referred to but which is not illustrated.

5 In order to prevent the spool 20 from overrunning itself and for the purpose of controlling its revolution, I have provided the brake band or cord 27 which is connected at 28 to the frame of the machine and 10 extends from its point of connection over a groove 29 in one flange of the spool and its opposite end is provided with a weight 30 as illustrated in Fig. 2 of the drawings.

The loop strands or threads 31 which may 15 be of any number as desired and which may be of any suitable and desirable material and of any color desired, are taken from spools which are supported upon spindles upon a rack not shown.

20 It will be understood that except for the fact that the spools are revolved for the purpose of permitting the thread to be unwound therefrom, they are stationary so that when the thread has been removed from 25 one spool it may be replaced by another without stopping the operation of the machine or in any way affecting the operation of the mechanism illustrated in the drawings and constituting my invention.

30 The loop strands are guided or conducted through the thread or strand guiding tube 34 which is supported in the plugs 33, 14 and 15 in the revoluble member 6 and is arranged in parallel relation to the axis of said 35 revoluble member. It is revolved bodily around the axis of the said revoluble member but is held against independent rotation or revolution about its own axis by reason of its connection at 35 with the upper 40 end of the link 36 pivoted at 37 to the lever 38 pivoted at 39 to a part of the frame of the machine.

This construction differs from that illustrated in my co-pending application, filed 45 July 1, 1911, Serial No. 636401, in which the rear end of the guide member for the loop strands or threads is held in substantially stationary position.

In the present construction the rear end 50 as well as the remainder of the guide member 34, travels through a circulatory reciprocating path.

Notwithstanding the fact that the member 34 revolves around the axis of the revoluble member 6 as well as around the member 12 it does not interfere in any way with the inner binding thread 13 for the reason that the said thread and the spool from which the same is drawn is caused to 60 revolve in the same direction and with the same speed as the said member 34.

40 designates a tubular former having a head 41 which is provided with notches 42 and 43.

65 The inner binding thread 13 passes

through the guide member 12 and through the notch 43 as indicated most clearly in Fig. 3 of the drawings and along the underside of the cylindrical portion of the former 40.

70

The loop strands or threads which pass through the guide member 34 extends from the forward end of the said member 34 and are wound around the stationary former 40 by reason of the revolution of the member 34.

75

The binding thread 13 is included within the coil of the said strands or threads 31 and are held between the same and an outside binding thread 44 which is supplied from a source of supply not shown and extends around a sheave or roller 45 and is carried into close proximity to the outer side of the coil or threads around the former 40 and in opposite relation to the binding 80 thread 13. The forward ends of the said binding threads are connected to a twister (not shown) which is of known construction and operates in a known manner and the said threads together with the ornamental 85 strands or threads which are held between the binding threads are drawn or fed forward and simultaneously twisted. An important function of the roller 45 is to feed the coiled ornamental threads and the binder 90 threads forward and at the same time control the forward movement of said threads.

90

As an additional means for causing a positive forward movement of ornamental threads on the former, I have provided the 100 endless cord 47, which may be of any suitable material, which extends through the tubular former 40 and around the guide rollers 48 and then in reverse direction through the notches 42 and along opposite 105 sides of the said former 40. The ornamental strands or threads are wound around the said cords which extend along the opposite sides of the former 40 and the travel of the latter in the direction indicated by the arrow 110 in Fig. 1 of the drawings causes the said threads which are coiled around the said former to be fed forward against the cutting knife 50 which preferably is circular and a portion of the edge of which projects 115 into a slot 51 formed in the upper side of the said former, as indicated most clearly in Fig. 4 of the drawings. The edge of the said knife is located in contact with the wall forming one end of the slot 51 as is indicated at 52 so as to prevent any of the threads which are to be cut by the knife from passing between the edge thereof and the edge of the end wall of the said slot. The cutting device is made circular in order 120 that when one portion thereof becomes dulled another portion thereof may be brought readily into cutting position.

115

The cutting member 50 is supported in any suitable manner upon an adjustable 125

120

125

130

bracket 54 which is supported upon a stationary bracket 55. The former 40 is also supported upon the said bracket 55 as is indicated at 56.

5 In this construction, as in the construction illustrated in my copending applications, the binding thread is taken from the spool 20 in untwisted condition but in the operation of the device such thread is twisted between the said spool and the point of its connection with the outside binding thread 44.

Having thus explained the nature of my said invention and described some of the ways of making and using the same although without attempting to set forth all of the forms in which it may be made or all the modes of its use, what I claim is:—

1. In a machine for making ornamental rope or cord, the combination of a stationary former, means for supporting and guiding inner and outer binding threads in operative relation to said former, a revoluble member spaced from the said former, a revoluble carrier for said inner binding thread supported coaxially with said revoluble member, the said inner binding thread extending from its carrier into the interior of said revoluble member and thence into operative relation to the said former, a support and guiding member for the ornamental threads or strands, which member is supported interiorly of the said first-mentioned revoluble member and in parallel relation to the axis thereof, means for holding the said supporting and guiding member against revolution about its own axis, and revolution of the first-named member causing revolution of the said supporting and guiding member around the portion of the said inner binding thread within the first-named revoluble member, such revolution causing the winding or coiling of the said loop threads or strands around the said former and the said inner binding threads, and means for drawing the thread from the inner binding thread carrier and thereby causing revolution of the same in the same direction as the said first-named revoluble member, and the said inner binding thread at its point of unwinding from the said carrier being held in constant relation to the said supporting and guiding means for the loop threads or strands.

2. In a machine for making ornamental rope or cord, the combination of a revoluble member, a loop thread or strand guiding device supported upon and extending through the said revoluble member, a stationary former supported independently of the said revoluble member, means for supporting and guiding inner and outer binding threads in operative relation to said former, which binding threads are adapted to be twisted together and the revolution of said revoluble member causing the coiling or winding

of the said loop strands or threads around the said former and around the said inner binding thread, and a severing device in operative relation to the said former for severing the said loop threads or strands. 70

3. In a machine for making ornamental rope or cord, the combination of a revoluble member, a loop thread or strand supporting and guiding device supported upon and extending through the said revoluble member eccentrically thereof, a stationary former, means independent of said revoluble member for supporting said former, means for supporting and guiding inner and outer binding threads in operative relation to said former, which binding threads are adapted to be twisted together, and the revolution of said revoluble member causing the coiling or winding of the loop threads or strands around the said former and around the said inner binding thread, an adjustable severing device in operative relation with said former for severing the said loop strands or threads after they are coiled or wound around the said former, and the said inner binding thread, and means for moving the said loop strands or threads on the said former against the said severing device for severing the same. 80

4. In a machine for making ornamental rope or cord, the combination of a revoluble member, a stationary former, means independent of said revoluble member for supporting the said former, means for supporting and guiding an outer binding thread in operative relation to said former, means coaxial with the said revoluble member for supporting and guiding the inner binding thread into operative relation with said former, a device for supporting and guiding loop threads or strands into operative relation to said former, the said device extending through the said revoluble member and being located a distance from the center thereof, means for holding the said device against revolution on its own axis and the revolution of the said member causing the coiling or winding of the said loop strands or threads around the said former and around the inner binding thread, and a severing device in operative relation to said former for severing the said loop threads or strands. 100

5. In a machine for making ornamental rope or cord, the combination of a revoluble member, a stationary former, means independent of said revoluble member for supporting the said former, means for supporting and guiding an outer binding thread in operative relation to said former, means coaxial with the said revoluble member for supporting and guiding the inner binding thread into operative relation with said former, a device for supporting and guiding loop threads or strands into opera- 120

tive relation to said former, the said device extending through the said revolute member and being located a distance from the center thereof, means for holding the said device against revolution on its own axis and the revolution of the said member causing the coiling or winding of the said loop strands or threads around the said former and around the inner binding thread, a severing device in operative relation to said former for severing the said loop threads or strands, and means for causing movement of the said loop strands upon the said former into contact with the said severing device, whereby said loop threads or strands are severed.

6. In a machine for making ornamental rope or cord, the combination of a revolute tubular member, a former supported independently of the said revolute member which former is coaxial with the said revolute tubular member, means for supporting inner and outer binding threads in operative relation to said former, a guiding device for the inner binding thread situated at the forward end of the said revolute tubular member and being coaxial therewith, a supporting and guiding device for the loop threads or strands which device extends through the said revolute tubular member and is supported thereon at a distance from the axis thereof and is parallel with such axis, a revolute carrier supporting a supply of the inner binding thread which carrier is coaxial with the said revolute member and with the said former and through which the said loop thread or strand guiding device extends and the revolution of the said revolute member causing the coiling or winding of the said loop threads or strands around the said former and around the said inner binding thread, and means for drawing off the binding thread and thereby causing revolution of the said carrier in the same direction as that of the revolution of the said revolute member, such means maintaining the inner binding thread at its point of separation from the said carrier in constant relation to the said loop thread or strand supporting and guiding device.

7. In a machine for making ornamental rope or cord, the combination of a revolute member, a stationary former supported independently of said revolute member, means for supporting inner and outer binding threads in operative relation to said former, means supported upon and extending through the said revolute member for causing the coiling or winding of loop threads or strands around the said former and around the said inner binding thread, a severing device for severing the loop threads or strands after the same are wound upon the said former, a cord having por-

tions located at opposite sides of the said former and between the same and the said coiled threads or strands upon the said former whereby movement of the said cord causes movement of the said loop strands upon the said former against the said severing device to sever the same.

8. In a machine for making ornamental rope or cord, the combination of a revolute member, a stationary former supported independently of said revolute member, means for supporting inner and outer binding threads in operative relation to said former, means supported upon and extending through the said revolute member for causing the coiling or winding of loop threads or strands around the said former and around the said inner binding thread, a severing device for severing the loop threads or strands after the same are wound upon the said former, an endless cord extending coaxially through the said former and around guides supported upon the said former, portions of the said cord extending thence upon opposite sides of the said former and being located between the same and the surrounding loop threads or strands whereby movement of the said cord causes movement of the said loop strands upon the former into contact with the said severing device for severing the same.

9. In a machine for making ornamental rope or cord, the combination of a revolute member, a former supported independently of and in axial alignment therewith, and a thread or strand guiding member supported upon and interiorly of the said revolute member in parallel relation to the axis thereof, one end of the said thread or strand guiding member being in operative relation to the said former.

10. In a machine for making ornamental rope or cord, the combination of a revolute tubular support, an ornamental thread guide and a binding thread guide both supported upon and interiorly of said support the one a distance away from the axis of said support and the other coincident with such axis, and a stationary former supported independently of said revolute support.

11. In a machine for making ornamental rope or cord, a revolute support, means for causing revolution thereof, an ornamental thread or strand guiding member supported by said revolute support at a point removed from the axis of said support, said thread or strand guiding member being in parallel relation to said support, a binding thread guide also supported upon said support, a former supported independently of said revolute support, the forward end of the said ornamental thread or strand guiding member extending over the rear end portion of said former and being revolved around the

same by the revolution of the said revoluble support.

12. In a machine for making ornamental rope or cord, the combination of ornamental and binding thread guiding devices, a revoluble member common to the said devices and supporting the same, a former supported independently of said revoluble member and around which thread from such ornamental thread guiding device is adapt-

ed to be wound, and means for supporting an additional binding thread in operative relation to said former.

In testimony that I claim the foregoing as my invention, I have hereunto signed my name this 28th day of June, A. D. 1911.

FRANKLIN W. OEHRLER.

In the presence of—

CYRUS N. ANDERSON,
GEO. H. WEIDNER.
